UNITED STATES PATENT OFFICE.

JOSEPH W. WEISMANTEL, OF NEWARK, NEW JERSEY.

STREET OR ROAD CLEANING APPARATUS.

Application filed August 9, 1923. Serial No. 656,822.

This invention relates, generally, to improvements in street or road-cleaning apparatus; and, the present invention has reference, more particularly to a novel apparatus 5 of the general character hereinafter more fully set forth, which is self-propelled, and which is especially designed for the purpose of removing snow, but which may also be employed for the removal of dirt and the 10 like from the paved surfaces of streets and highways.

With the purposes of the invention above stated, the invention has for its principal object to provide a cleaning apparatus which 15 is self-propelled, and in which the various devices and parts are of simple construction, and have been effectively arranged, so that the apparatus will properly remove snow and particles of ice from the paved surfaces 20 of streets and highways, the snow and ice collected within the apparatus being readily melted and turned into water.

Other objects of the present invention not at this time more particularly enumerated will be fully understood from the detailed description of the present invention.

With the various objects of the present invention in view, the said invention consists, primarily, in the novel street and road-cleaning apparatus hereinafter set forth; and, the said invention consists, furthermore, in the novel arrangements and combinations of the various devices and parts, as well as in the details of the construction 30 of the said parts, all of which will be more fully described in the following specification, and then finally embodied in the clauses of the claims which are appended to and which form an essential part of the said 35 specification.

The invention is clearly illustrated in the accompanying drawings, in which:—

Figure 1 is a side elevation of a street or road-cleaning apparatus, showing one embodiment of the principles of the present invention; Figure 2 is a longitudinal vertical section of the same; Figure 3 is a part plan or top view and horizontal sectional representation of the apparatus; and Figure 4 is a detail view of a portion of the casing of the apparatus, looking in the direction of and at the point indicated by the arrow α in said Figure 3, showing an outlet for the water and dirt from within the apparatus, the cover-plate for said opening being shown removed in said Figure 4.

Similar characters of reference are employed in the several figures of the drawings, to indicate corresponding parts.

Referring now to the several figures of the drawings, the reference-character 1 indicates a complete street or road-cleaning apparatus made according to and embodying the principles of the present invention, the same being constructed, preferably, in the form of a motor-driven vehicle, as here shown. This vehicle consists, essentially, of a suitably constructed chassis-frame 2, comprising any usual form of axle-bearings, in which are rotatably mounted the front axle 3 and the rear axle 4, said axles being respectively provided with the wheels 5 and 6. Suitably mounted upon said chassis-frame is a suitably constructed casing or shell 7 which provides an enclosure for the operating mechanism of the vehicle, said casing or shell being provided in its top or roof with suitably located ventilators 8, substantially as shown and for the purposes to be hereinafter more fully set forth. At the forward end 80 of the vehicle, and adjacent to the vertical wall 9 of the said casing or shell, a suitable vestibule 10 for the driver and operator of the vehicle may be provided, and 11 indicates the usual engine-hood which is located 85 in any usual manner about the motor for driving the vehicle and for operating the various mechanisms of the same.

The means for transmitting power from the engine or motor to the rear axle 4 of the vehicle being of any of the well-known constructions, such mechanism is not described in the present specification, nor has the same been illustrated in the accompanying drawings, as this is deemed unnecessary. At or near the rear end-portions of the longitudinally extending members of the chassis-frame is a laterally disposed rod 12, provided with pinions 13 and a crank 14 for operating the same. In mesh with the teeth of said pinions 13 is a toothed sector or rack 15, the main members at the ends of the said sector or rack being provided with bearing-100 portions 16 in which is rotatably supported a laterally extending shaft 17.

The said members of the toothed sector or rack are also provided with bracket-like portions 18 having bearings, as 19, in which is rotatably mounted the laterally extending shaft 20 of a rotary sweeper-brush 21. This brush is partially enclosed within a hood or cover, as 22, and is located in close prox-105

imity to an inlet-opening 24 formed in the vertical end-wall 23 of the previously mentioned shell or casing 7. Upon the rear axle 4 is a sprocket-wheel 25, the said shaft being also provided with a sprocket-wheel 26, a link-chain or drive 27 being employed with said sprocket-wheels 25 and 26 for actuating the said shaft 20.

The axle 4 is also provided with another 10 sprocket-wheel 23 over which is arranged a link-chain or drive 29 which also passes over a sprocket-wheel 30 upon a laterally extending shaft 31 which is rotatably mounted in bearing-members 32 secured to 15 and extending downwardly from the chassis-frame 2. Extending laterally across the upper portion of the chamber formed by said shell or casing 7 is a shaft 33 which is provided with a pulley-wheel 34 over which is 20 arranged a belt 36 passing over and receiving its power from a pulley-wheel 35 with which the previously-mentioned shaft 31 is provided. The reference-character 37 indicates a conveyor or apron arranged about 25 the said shafts 17 and 33 in a suitable manner and adapted to be properly actuated from the rotary motion of said shaft 33. Within the chamber formed by the said shell or casing 7 is a receiving compartment 38 formed by a portion of the end-wall 9 of the shell or casing 7, and suitably disposed wall-members 39 and 40, and a base-member 41, the upper portion of said compartment 38 being open, as will be evident 30 from an inspection of Figure 2 of the drawings.

Pivottally disposed or hinged, as at 42 and 43, in said open part of the compartment 38, are receiving elements 44 and 45 40 which are adjustably suspended in their respective positions, by means of chains 46, or other suitable flexible connections, the free controlling ends of which lead into the vestibule 10, where said ends may be suitably fastened, and may be manipulated by 45 the operator of the vehicle, when it is desired to raise or lower said elements 44 and 45.

Suitably disposed within the chamber 50 formed by the said shell or casing 7, at a point between the rear end-wall 23 and the conveyor or apron 37 is a compartment, as 47, formed by an arrangement of wall-members 48, 49 and 50, with a portion of the 55 said rear end-wall, in which is suitably located a filler-element 51 provided with a suitable closing cap 52, for supplying the said compartment with a liquid fuel, such as crude oil, or the like.

60 Also suitably secured to the chassis-frame of the vehicle is an element 53, in the form of an air-forcing and compressing means or pump, the axle or shaft 54 of which is provided with a sprocket chain, as 57, which in 65 turn passes over a sprocket-wheel 56 mount-

ed upon the previously mentioned shaft 31, and from which it receives its motion for operating the shaft 54 and the air-forcing and compressing means or pump located within the element 53. Means for conducting the compressed air from within the element 53 to within the fuel-containing compartment 47, so as to bring the liquid fuel therein under compression, is in the form of a pipe or duct 58, leading from said element 53 to the compartment 47, as shown, and which pipe or duct may be provided with a pressure-indicating gauge 59, preferably placed within the vestibule 10, so as to be easily observed by the operator of the vehicle. Suitably connected with and leading from the interior of the compartment is a fuel-conducting pipe 60, in which may be placed a suitable pressure-annunciator or gauge 61, as indicated in dotted outline in Figure 2, and which pipe 60 may also be provided with suitably constructed oil-burners or heaters, as 62, suitably arranged so as to be located directly above the receiving element 44, and when lighted, that the heat produced will be conveyed directly to said receiving elements 44 and 45. That a proper mixture of oil and air may be had at the burners or heaters, branch-connections 63 are made between the pipe 58 and the burners, whereby some of the air which is being forced through the pipe 58 will also be fed into the burners, as will be evident.

Suitably disposed within the compartment 38, and preferably upon the bottom 41 thereof, is a water-tight auxiliary shell or casing 64, provided with suitably disposed bearings 65 in which is rotatably mounted a longitudinally extending gear-shaft 66 provided upon its respective ends with bevel-gears 67 and 68. Motion of the shaft 66 is produced by means of a bevel-pinion 69 in mesh with the gear 67, said pinion 69 being mounted upon a shaft 70, which also carries a pulley-wheel 71. Passing over said pulley-wheel 71 is a drive-belt 72, which receives motion from a driving pulley 73 mounted upon the previously mentioned shaft 31.

Extending laterally across the lower portion of the compartment 38 is a suitably mounted shaft 74 having mounted thereon a bevel-gear 75 which is in mesh with the bevel-gear 68 for driving said shaft 74. Mounted upon said shaft 74, on opposite sides of the said shell or casing 64, are suitably formed conveyor-worms, as 76, the helices of which extend in opposite directions, as shown in Figure 3 of the drawings, the discharging end of each worm terminating in front of a discharging opening or outlet 77 located in each longitudinally extending side-wall of the main shell or casing 7. Cover-plates 78 are removably placed over said openings or outlets 77, said plates

being held in place by an arrangement of screw-threaded studs 79 and wing-nuts 80, as will be evident from an inspection of the several figures of the drawings.

- 5 From an inspection of Figure 2 of the drawings, it will be seen that when the apparatus is to be used as a snow and ice-remover, the burners 62 are lighted, and the vehicle being set in motion, the rotary broom 10 19 will force the snow directly upon the conveyor-belt 37, which carries the snow upwardly into the main compartment 7 and discharges it into the pan-shaped melting elements 44 and 45. The heat from the 15 burners or heaters 62 turns the snow and ice into water, which passes from the said elements 44 and 45 into the compartment 38, where the water is collected. As soon as this compartment has been suitably filled, the 20 vehicle may be driven along side of a sewer-basin, or other dumping place, where the cover-plates 78 are removed, to permit the conveyor-worms 76 to force the water from the compartment 38. It will also be evi- 25 dent, that at times the worms 76 need not be set in motion, in which case the collected water is permitted to flow by its own gravity from the uncovered discharging openings or outlets 77.
- 30 In lieu of using the apparatus as a snow-remover, it may be used as a street-sweeper for removing dirt from the paved surface of the street. In that case the burners or heaters 62 are not lighted, but the hinged 35 elements 44 and 45 are suitably lowered, so that the dirt which is being conveyed into the main compartment 7 is discharged directly into the compartment 38, and is then forced by means of the conveyor-worms 76 40 from the uncovered openings or outlets 77 of the apparatus, as will be evident.

When the apparatus is to be used as a street-flusher, the apparatus is provided with an auxiliary air-compressor or pump 45 80', the pump-shaft 81 of which is provided with a sprocket-wheel 82, over which passes a link-belt 83 which receives its motion from a sprocket-wheel 84 carried by the previously mentioned shaft 54. Air is sucked into 50 the casing which surrounds the pump-mechanism by means of an arrangement of suitably constructed suction-valves 85.

Within the compartment 38, and in communication therewith, is a water-receiving 55 chamber 86, see said Figure 2 of the drawings, in which the water may be brought under pressure of air from the compressor or pump 80 through a pipe 87, or from the compressor or pump 53 through the pipe 58 60 and a branch-pipe 88 which connects said pipe 58 with the interior of said water-receiving chamber 86.

Suitably connected with and leading from 65 said chamber 86 is a water-conveying pipe 89, secured in its position to the side of the

chassis-frame 2, by means of a suitably constructed bracket 90, or other fastening means, said pipe 89 being provided at its lower end-portion, near the street-surface, with a suitably formed outlet-nozzle 91, 70 which is usually of the "squeegee" type, as here shown. If desired, a forwardly extending branch-pipe 92 may be connected with said pipe 89, the pipe 92 being also provided at its discharge end with a similar 75 outlet-nozzle 93. The operation of this street-flushing mechanism will be fully understood from an inspection of said Figure 2 of the drawings, and any further description of the same is therefore unnecessary. 80

The apparatus may also be provided with suitably disposed brackets, as 94, or other suitably securing means, for vertically adjustable relation upon the side of the vehicle, of a stem 95 carrying upon its lower 85 end-portion a pivotally disposed road-scraper, as 96, which is maintained in its pivotal relation by means of the usual holding chains 97.

The various operations of which the apparatus is capable will be clearly understood from the foregoing description and from an inspection of the several figures of the drawings, and any further description of the same is therefore deemed unnecessary. 90

95 Of course, I am fully aware that many changes may be made in the general arrangements and combinations of the various devices and parts, as well as in the detailed arrangements and construction of the said parts, without departing from the scope of the present invention, as set forth in the foregoing specification, and as defined in the clauses of the claims which are appended to and which form an essential part of the said specification. Hence, I do not limit my present invention to the exact arrangements and combinations of the various devices and parts as described in the said specification, nor do I confine myself to the 100 exact details of the construction of the said parts, as illustrated in the accompanying drawings.

I claim:—

115 1. A street or road-cleaning apparatus in the form of a motor-propelled vehicle, comprising a main compartment having a water-receiving chamber in its lower portion, burners within the upper portion of said main compartment, means for supplying 120 liquid fuel to said burners, means for conveying snow into the upper portion of said main compartment and beneath said burners, adjustable means within said main compartment to support introduced snow subject to 125 the melting action of said burners, said supporting means being adapted to drain the melted snow into said water receiving chamber, said compartment having in a side thereof an outlet opening leading from said 130

water receiving chamber, a removable cover to normally close said outlet opening, and a rotary conveyor worm in the bottom of said water receiving chamber having its discharge end cooperating with said outlet opening.

2. A street or road-cleaning apparatus in the form of a motor-propelled vehicle, comprising a main compartment having a water-receiving chamber in its lower portion, 10 burners within the upper portion of said main compartment, means for supplying liquid fuel to said burners, means for conveying snow into the upper portion of said compartment and beneath said burners, and 15 a pair of open ended melting pans to receive and support introduced snow subjects to the melting action of said burners, said pans being disposed end to end with their adjoining ends overlapping and vertically spaced apart to provide a drainage passage 20 for melted snow leading to the underlying water receiving chamber, said compartment having in a side thereof an outlet opening leading from said water receiving chamber, and a removable cover to normally close said 25 outlet opening.

3. A street or road-cleaning apparatus in the form of a motor-propelled vehicle, comprising a main compartment having a water-receiving chamber in its lower portion, 25 burners within the upper portion of said main compartment, means for supplying liquid fuel to said burners, means for conveying snow into the upper portion of 30 said main compartment and beneath said burners, a pair of open ended melting pans to receive and support introduced snow subject to the melting action of said burners, 35 said pans being disposed end to end with their adjoining ends overlapping and vertically spaced apart to provide a drainage passage for melted snow leading to the underlying water receiving chamber, and means 40 for adjusting said pans.

4. A street or road-cleaning apparatus in the form of a motor-propelled vehicle, comprising a main compartment having a water-receiving chamber in its lower portion, 45 burners within the upper portion of said

main compartment, means for supplying liquid fuel to said burners, means for conveying snow into the upper portion of said main compartment and beneath said burners, a pair of open ended melting pans to receive 50 and support introduced snow subject to the melting action of said burners, said pans being disposed end to end with their adjoining ends overlapping and vertically spaced apart to provide a drainage passage 55 for melted snow leading to the underlying water receiving chamber, said compartment having in a side thereof an outlet opening leading from said water receiving chamber, and a removable cover to normally close said 60 outlet opening.

5. A street or road-cleaning apparatus in the form of a motor-propelled vehicle, comprising a main compartment having a water-receiving chamber in its lower portion, 65 burners within the upper portion of said main compartment, means for supplying liquid fuel to said burners, means for conveying snow into the upper portion of 70 said main compartment and beneath said burners, a pair of open ended melting pans to receive and support introduced snow subject to the melting action of said burners, 75 said pans being disposed end to end with their adjoining ends overlapping and vertically spaced apart to provide a drainage passage for melted snow leading to the underlying water receiving chamber, means for adjusting said pans, said compartment having in a side thereof an outlet opening leading 80 from said water receiving chamber, a removable cover to normally close said outlet opening, and a rotary conveyor-worm in the bottom of said water receiving chamber having its discharge end cooperating with 85 said outlet opening.

In testimony, that I claim the invention set forth above I have hereunto set my hand this 30th day of July, 1923.

JOSEPH W. WEISMANTEL.
